HANDLE FOR SPOONS, &c.

No. 20,077.

Patented Aug. 5, 189

Fig. 1.

Fig. 2.

UNITED STATES PATENT OFFICE.

AUSTIN F. JACKSON, OF TAUNTON, MASSACHUSETTS, ASSIGNOR TO THE REED & BARTON CORPORATION, OF SAME PLACE.

DESIGN FOR A HANDLE FOR SPOONS, &c.

SPECIFICATION forming part of Design No. 20,077, dated August 5, 1890.

Application filed July 7, 1890. Serial No. 358,006. Term of patent 14 years.

To all whom it may concern:

Be it known that I, AUSTIN F. JACKSON, residing at Taunton, in the county of Bristol and State of Massachusetts, have invented and produced a new and original Design for Handles of Table-Spoons, Forks, &c., of which the following is a specification.

My design is fully shown in the accompanying photographic illustration, in which—
10 Figures 1 and 2 represent, respectively, the front and back of a spoon-handle.

The design for the front *a* is mainly floral and in part arabesque, while that for the back *b* includes an irregularly-shaped panel with 15 flowers and arabesques.

It is not intended the design shall be re-

stricted to spoons and forks, but applied also to handles of ladles, knives, &c.

What I claim is—

1. In the design for a handle for spoons, &c., the front or face of the handle, as shown in accompanying photographic illustration. 20

2. In the design for a handle for spoons, &c., the back of the handle, as shown in accompanying photographic illustration. 25

3. The design for the ornamentation of the handles of spoons, &c., as shown in accompanying photographic illustration.

AUSTIN F. JACKSON.
